UNITED STATES PATENT OFFICE.

FRANK A. BUELL, OF BROOKLYN, NEW YORK.

SAW-HANDLE.

SPECIFICATION forming part of Letters Patent No. 314,562, dated March 31, 1885.

Application filed August 11, 1884. (No model.)

To all whom it may concern:

Be it known that I, FRANK A. BUELL, of Brooklyn, in the county of Kings and State of New York, have invented a new and Improved 5 Saw-Handle, of which the following is a full, clear, and exact specification.

The object of my invention is to provide a new and improved saw-handle, which is simple in construction, strong, durable, and cheap.

10 The invention consists in certain improvements in that class of saw-handles that are formed of wood and have metal re-enforcing plates secured to their lower edges, as will be hereinafter fully described and claimed.

15 Reference is to be had to the accompanying drawings, forming part of this specification, in which similar letters of reference indicate corresponding parts in both the figures.

20 Figure 1 is a side view of my improved saw-handle. Fig. 2 is a cross-sectional elevation of the same on the line $x x$, Fig. 1.

The saw-handle A is provided with a metal bottom bridge, B, terminating at its outer end in the horn C. In the inner surface of the 25 bridge B a dovetailed groove is formed to receive a dovetailed ridge, D, on the bottom of the wooden part of the handle. A screw, E, is passed through the metal bridge into the corresponding part of the wooden part of the 30 handle, to prevent the bridge from shifting.

In the bottom surface of the bridge a groove is formed for receiving the upper edge of the tongue F' of the saw-blade F. The inner end parts of the handle and bridge are slotted to receive the butt-end of the blade F.

35

By constructing the handle in the manner shown and described the wooden part can be sawed out in one operation, whereas in making the usual wooden handles the outside must be sawed out by means of a band-saw and the inner part sawed out by means of a gig-saw, which makes the handles quite expensive.

The metal horn cannot break off, as the wooden horns do.

The metal bridge, which may be made of 45 brass, iron, steel, &c., is shaped like the usual wooden bridge.

Having thus described my invention, what I claim as new, and desire to secure by Letters Patent, is—

50

A wooden saw-handle having a metal bottom bridge provided in its upper surface with a dovetailed groove for receiving a dovetailed ridge on the bottom of the wooden part of the handle, substantially as herein shown and described.
